[57] CLAIM

The ornamental design for a scraper for jars of baby food, as shown and described.

DESCRIPTION

FIG. 1 is a perspective view of a scraper for jars of baby food showing my new design;

FIG. 2 is a top plan view thereof, the jar shown in broken lines for illustrative purposes only;

FIG. 3 is a top plan view thereof, the jar shown in broken lines for illustrative purposes only;

FIG. 4 is a top plan view thereof;

FIG. 5 is a bottom plan view thereof;

FIG. 6 is a right-side elevational view thereof;

FIG. 7 is a left-side elevational view thereof;

FIG. 8 is a front elevational view thereof, drawn to an enlarged scale;

FIG. 9 is an elevational view thereof, drawn to an enlarged scale;

FIG. 10 is a cross-sectional view thereof, taken along the lines 10—10 of FIG. 3, and drawn to an enlarged scale;

FIG. 11 is a cross-sectional view thereof, taken along the lines 11—11 of FIG. 3, and drawn to an enlarged scale;

FIG. 12 is a cross-sectional view thereof, taken along the lines 12—12 of FIG. 3, and drawn to an enlarged scale.
